CLAIM

I claim the ornamental design for trousers with tilted bottom hem, as shown and described.

DESCRIPTION

FIG. 1 is a front view of trousers with tilted bottom hem showing my new design;

FIG. 2 is a back view thereof;

FIG. 3 is a right side view thereof; and,

FIG. 4 is a left side view thereof.

The broken line depiction of trouser with tilted bottom hem parts in FIGS. 1-4 are for illustrative purposes only and form no part of the claimed design.
